Patented Feb. 11, 1902.

S. SCHLANGEN.

BUNG.

(Application filed Nov. 16, 1899.)

(No Model.)

UNITED STATES PATENT OFFICE.

SIMON SCHLANGEN, OF CHICAGO, ILLINOIS, ASSIGNOR, BY MESNE ASSIGNMENTS, TO THE SCHLANGEN CO., A CORPORATION.

BUNG.

SPECIFICATION forming part of Letters Patent No. 693,314, dated February 11, 1902.

Application filed November 16, 1899. Serial No. 737,201. (No model.)

To all whom it may concern:

Be it known that I, SIMON SCHLANGEN, a resident of Chicago, in the county of Cook and State of Illinois, have invented certain 5 new and useful Improvements in Bungs, of which the following is a specification.

My invention relates to bungs; and its object is to provide a bung automatic in operation—that is, one which is normally in closed 10 position and which must be opened when it is desired to either insert or remove the bung from the bung-opening.

In the drawings, Figure 1 is a section, partly in elevation, of my bung and operating-key; 15 Fig. 2, an elevation of such bung and a portion of the key; Fig. 3, a plan view of the bung, and Fig. 4 a plan of the top plate removed.

My bung may be used in connection with 20 either a bung-bushing or with a simple bung-opening in the barrel, keg, or the like, as desired, and in this application I have preferred to show it in the latter way—that is, in connection with the simple bung-opening—for 25 the reason that with my bung a bushing is not necessary, although it may be used if it should be so desired.

The stave 1 of the barrel is provided with a bung-hole 2, preferably having its outer 30 and inner edges or faces beveled or reamed out. In general terms the bung comprises several sections, which are movable with respect to each other, but which are normally held in compact relationship by means of a 35 spring, and which when in such compact form press an elastic member outwardly to seat in the lower part of the bung-opening, and thereby seal the same. The tendency of the bung is to automatically seat itself, and it can be 40 unseated and removed only by changing this compact relationship—that is, by moving the parts on each other by pressure applied by a key or otherwise.

As shown, the bung proper comprises the 45 following parts: A shell 3 has a lower cylindrical portion and an annular portion 4, provided with a lip 5, extending over the rabbeted margin of a circular top plate 6. This plate has a cylindrical portion 7, received by 50 an inner cup or cylinder 8, which is provided

at its top margin with an annular flange 9, fitting, preferably, closely, but operatively, within the shell 3. A packing-nut 10, pressed or threaded into the cylinder 7, so as to be flush with the top plate, presses against suitable packing 11, resting in the bottom of such cylinder and through which passes a movable rod or plunger 12, having a head 13. A shoulder 14 is riveted over onto a washer 15, so as to secure to the plunger the cylinder 16, as well as an expanding-ring 17, having an inwardly-turned marginal flange 18. A coiled spring 18 lies in the annular space between the cylinders 3 and 8 and bears, respectively, against the flange 9 and a flange 65 3^a on the lower end of the cylinder 3. The tendency of this spring is to hold the cylinder 8 within the cylinder or shell 3 and also to hold the expanding ring or plate 16 up as closely as possible, so that all the parts will 70 be in compact relationship. A ring 19 extends around the outside of shell 3 and is provided with a flange 20. The shell 3 is beaded at 21 and 22 above and below this ring, so as to hold it in proper position. The 75 elastic member which I prefer to use consists of a cup or sack 23, having a thickened side portion 24 and thin end or bottom portion 25, and the same may be secured to the ring 19 by means of a wire 26 or in any other suitable 80 manner. The rubber may have a groove molded in it to receive flange 20. This elastic member may consist of rubber and is preferably in the form of a sack, so as to seal all the parts of the bung, both to prevent the escape of any 85 gas and also to protect the bung from the action of the contents of the barrel. When the bung is in normal position, as shown, it automatically closes the bung-hole, inasmuch as the spring draws an expanding-ring against 90 the thickened part of the rubber, throwing it outward against the beveled face or surface of the bung-hole, so that not only is the hole sealed, but the bung is prevented from being withdrawn or blown out. The greater the 95 pressure in the barrel the tighter the fit. It is obvious that the bung will remain in this normally-closed condition until the plunger 12 is depressed or forced inward, so as to relieve the pressure of the expanding-ring 100

against the elastic member, which will not only unseat the same, but permit the whole bung to be withdrawn.

The instrument or key for opening and withdrawing the bung contemplates in general terms a plunger for forcing the rod 12 inward. The key which I have shown as suitable for this purpose comprises a body portion or stem 27, having a right-angled half-handle 28. A half-handle 29, which with the other half-handle makes a handle complete in form when the parts are brought together is pivoted in the upper part of this stem and provided with a cam-head 30. This cam is adapted to bear against the plunger 31, movable longitudinally in the stem, and to depress it against the tension of spring 32. To accommodate and attach the remaining parts to be described, a pin 33 is screwed into the lower end 20 of the plunger, although it is obvious that the plunger itself may be extended and pointed for the same purpose of depressing the plunger 12 in the bung. The stem 27 has two downwardly-extending portions 34, which 25 may rest on the top of the bung when in position, as seen in Fig. 2. A plate 35 is screwed or otherwise secured to the stem 27, as shown in Fig. 1, and provided with downwardly-extending fingers or hooks 36, having 30 a slot or notch 37, which hooks are adapted to be inserted through openings or slots 38, extending through the plates 4 and 6 of the bung. A plate 39 is secured to the pin 33 by means of an integral nut 40 and is movable 35 therewith. On its diagonal corners it has downwardly-projecting fingers 41, preferably having their lower outer faces beveled, as at 42. In operation the hooks 36 are first inserted in the slots 38, and the handle 29 is thereupon 40 swung closed upon the handle 28, which is made slightly shorter, so that the parts may be easily separated. This handle movement depresses fingers 41, whose beveled faces striking the ends of the slots on either side 45 of the hooks act as wedges to partially rotate the entire key, thereby causing the slots 37 to engage the other ends of the slots 38 and locking the key and bung together. Simultaneously the pin 33 forces rod 12 inward and 50 forces the expanding-ring away from engagement with the thickened portion of the rubber cup and also forces such ring against the lower portion of such cup, so that by pulling on the key the entire bung is free to be removed from the barrel. To insert the bung, the handle parts are first brought together to hold the bung-sections in their open position, just as they were when withdrawn. The bung 55 is then inserted in the bung-hole, and handle 60 29 is then raised to the position seen in Fig. 1, whereupon the spring will automatically expand the rubber cup, and the key is then free to be withdrawn, the fingers 41 being automatically withdrawn by means of the 65 plunger 31 to allow the key to be manually partially turned to permit withdrawal of the hooks 36 from the slots. The function of the

fingers 41 is to fill the spaces of the slots 38 that would otherwise remain open after the key had been partially turned to cause engagement between the bung and notches 37. The filling of these spaces permits the key and bung to be securely locked together when the plunger 31 is depressed, so that the key may be turned in either direction for any purpose and as an accommodation to the operator. In case such fingers 41 were not used it would obviously be necessary to always turn the key and bung in the withdrawing operation in one and the same direction or otherwise the key would slip out of the bung. These fingers thus hold the notches 37 in engagement with the bung-body, and such engagement cannot be broken until the handle 29 is raised, so as to permit the plunger 31 to be restored to normal position.

By the use of my invention I provide a bung which obviates many of the objections to devices of this class. The automatic feature is particularly valuable, because it is impossible to force the elastic member too tightly or too loosely upon its seat. The pressure on the seat is determined by the tension of the spring, which may be of any desired tension. In the form of bungs in which members screw upon each other to close the bung there is danger of too tight seating and the destruction and injury of the parts. These objections, among others, are avoided in my type of bung, which is automatic in action. Moreover, by the use of the peculiar construction of elastic member, which is in the form of a sack, the gas is prevented from escaping, because the same completely envelops the lower portion of the bung, so that the bung is protected from the contents of the barrel.

Although I have described more or less precise forms and details of construction, I do not intend to be understood as limiting myself thereto, as I contemplate changes in form, the proportion of parts, and the substitution of equivalents as circumstances may suggest or render expedient and without departing from the spirit of my invention.

I claim—

1. A bung comprising a shell or casing, a cylinder normally spring-pressed therein, a plate secured to the shell and having a cylindrical portion received by such cylinder and forming a guide and stuffing-box, an expanding ring or plate having an upwardly-turned flange, an elastic member secured at its top to the shell and normally expanded against the bung-opening and a rod or plunger secured both to the cylinder and ring and passing through such stuffing-box.

2. A bung comprising a shell or casing, a cylinder normally spring-pressed therein, a top plate 6 secured to the margin of the shell and having a hollow inwardly-extending cylindrical portion received by said cylinder, an expanding-ring having a marginal upturned flange, a rod secured both to the cylinder and ring and an elastic member consisting of a

cup or sack of elastic material, secured at its top to the shell or casing and adapted to be normally expanded to seat by contact of such flange against its sides and to be unseated when such rod and ring are forced inward against the bottom of such sack.

3. A bung comprising a shell 3, a cylinder 8 having flange 9, a spring 18 abutting respectively the bottom of the shell and such flange, a top plate 6 having a cylindrical portion 7 received by cylinder 8, packing 11, a packing-nut screwing in such portion 7 to hold the

packing, a ring 16 having a flange 17, a rod 12 secured to the plate 16 and bottom of cylinder 8 and extending through such packing 15 and its nut and an elastic cup or sack having thickened sides 24 and thin bottom portion 25, said top plate having slots for the reception of a key.

SIMON SCHLANGEN.
